UNITED STATES PATENT OFFICE.

GEORGE A. LUTZ, OF NEW YORK, N. Y., AND CLARENCE C. SIBLEY, OF PERTH AMBOY, NEW JERSEY.

FLEXIBLE CONDUIT.

No. 825,227.

Specification of Letters Patent.

Patented July 3, 1906.

Application filed March 14, 1905. Serial No. 250,053.

To all whom it may concern:

Be it known that we, GEORGE A. LUTZ, residing in New York city, borough of Brooklyn, New York, and CLARENCE C. SIBLEY, residing in Perth Amboy, Middlesex county, New Jersey, citizens of the United States, have invented certain new and useful Improvements in Flexible Conduits, of which the following is a specification.

10 Our invention relates to improvements in the class of flexible conduits which have an insulating paper tube or lining inclosed within a fabric cover, usually woven or braided thereon, within which conduit an electric wire or conductor is to be placed. In installing such conduits workmen frequently find the wire to be inserted too large to readily enter the bore of the tube or lining, and they remove such paper tube or lining by pulling the same from its fabric cover, which materially reduces the insulating qualities of the conduit with consequent risk and danger.

25 The object of our invention is to prevent the paper tube or lining in such class of conduits from being readily removed from the outer cover, to thereby prevent the use of the conduit without having the tube or paper lining therein, and in carrying out our invention we weaken the paper tube or its convolutions at any desired number of places, preferably by cutting slits in the paper from edge to edge, whereby if a workman attempts to withdraw the paper tube or lining from the outer cover the paper will readily tear near 35 or close to the end of the conduit, the rest of the paper remaining in the conduit.

30 Reference is to be had to the accompanying drawings, forming part hereof, wherein—

Figure 1 is a partly broken side view of a 40 piece of flexible conduit embodying our invention. Fig. 2 is a cross-section on the line 2 2 in Fig. 1. Fig. 3 is a cross-section on the line 3 3 in Fig. 1 through the inner tube or lining of the conduit, the wall of the weakened part being opened out to disclose the construction. Fig. 4 is a perspective view of a portion of the tube or lining, showing the manner of weakening the walls of the same; and Figs. 5 and 6 are details of modifications.

45 50 Similar numerals of reference indicate corresponding parts in the several views.

The conduit shown in the accompanying drawings is mainly of well-known class, having a spirally-wound paper tube or lining 1

and a cover 2 braided, woven, or otherwise applied thereon, all of which may be rendered fireproof or waterproof by suitable treatment in any well-known manner.

55 The strip of paper or other insulating material from which the tube or lining 1 is made is weakened in different places at suitable distances apart by reducing the thickness of the paper, and this may be done by cutting into the paper at 1^a, preferably from its outer surface toward its inner surface, in a direction at an angle to or transversely of its length, whereby tongues or laps 1^b are formed, said tongues being preferably left upon and integral with the body of the paper, so as to be laid back over the cut or slit 1^a to 70 assist in retaining substantially the normal thickness of the wall of the paper and providing a finished surface over the weakened parts 1^a, upon which the fabric 2 is applied. The cuts or weakened places 1^a may be made 75 in the paper strip by any suitable tool just as the paper is being wound upon a mandrel, or the slits could be made in the paper after the spirally-wound lining or core is made. In either case the covering 2 will be applied 80 upon the tube 1 after the walls are weakened, and the threads or fabric of the core will hold the tongues 1^b securely down upon the main body portion of the inner tube 1.

85 In Fig. 6 the paper strip is indicated as weakened by a cut 1^a on its inner surface, which cuts may be at suitable distances apart, and in Fig. 5 the paper strip has cuts 1^a in its edges, whereby the strip is weakened.

90 The arrangement above described is such that the flexible tube may be used in well-known manner for receiving electric wires; but if a workman should desire to remove the tube or lining 1 from the cover 2 by attempting to pull the tube through the end of the 95 cover such tube would tear at one of the weakened places 1^a, and the workman could then remove but a small portion of the tube, and at each further attempt to remove the tube from the cover 2 but a small piece could 100 be pulled out, the cover 2 closely and firmly gripping the tube 1.

105 It will be obvious that the walls of the tube 1 can be weakened without cutting into the same in the precise direction or at the exact angle shown in the drawings and that a substantially similar weakening of the walls of the tube may be made by lines of perfora-

tions across the same at suitable distances apart instead of cuts shown.

In our application for patent filed April 3, 1906, Serial No. 309,605, we have specifically 5 claimed a conduit in which the walls of the tube are weakened by perforations.

Having now described our invention, what we claim is—

1. A conduit for electric wires comprising 10 an inner tube made of a spirally-wound strip of insulating material having its walls weakened at various places, and a cover inclosing said tube, substantially as described.
2. A conduit for electric wires comprising 15 a spirally-wound strip of paper having its walls reduced in thickness at a plurality of places, and a fabric cover over said paper strip, substantially as described.
3. A conduit for electric wires comprising 20 a spirally-wound strip of paper having a plurality of cuts entering the same, and a cover over said strip, substantially as described.
4. A conduit for electric wires comprising 25 a tube formed of a spirally-wound strip of insulating material having a plurality of cuts entering the same providing tongues, and a

fabric cover over said tube and over said tongues holding said tongues upon the main part of the tube, substantially as described.

5. A conduit for electric wires comprising 30 a spirally-wound strip of paper having a plurality of cuts extending from edge to edge of the strip, and a fabric cover over said strip, substantially as described.

6. A conduit for electric wires comprising 35 an inner tube made of a spirally-wound strip of material having its walls weakened at a plurality of places, and a cover inclosing said tube, substantially as described.

7. A conduit comprising a suitable covering, a lining arranged therein composed of a strip of suitable material arranged in a spiral form and weakened at various places, whereby a pull upon said lining will cause the latter to separate at the weakened points instead 40 of at the joints of the spiral.
